UNITED STATES PATENT OFFICE.

LEWIS A. COCKLIN, OF GRISWOLD, IOWA.

LIQUID-FUEL BURNER.

Application filed December 11, 1925. Serial No. 74,709.

This invention relates to that class of liquid fuel burners consisting of an annular chamber for containing the fuel to be burned; a draft aperture centrally of the chamber for directing air upwardly therethrough and a cap for spreading the flame. The present invention has for one of its objects to provide means for breaking up and causing an undulating or rolling movement of the generated gases while they are moving radially from the chamber to cause a more complete combustion. Another object is to provide a metallic annular plate or flange outwardly of the cap and outwardly of the chamber and to be an integral part of the outer wall of the chamber as an aid in generating and controlling the movements of gas, said annular flange to be provided with a series of annular depressions, each outer depression being disposed in a plane somewhat higher than the next inner depression, the upright walls of the depressions to operate as detents or buffers for the control mentioned, said flange and outer wall to have an adequate thickness for retaining and communicating heat to the contents of the chamber as an aid in generating gas. Another object is to provide an annular support and a removable, asbestos wick in the chamber to cause a uniform distribution of the liquid fuel and uniform combustion. Other objects of the invention will be mentioned hereinafter.

In the accompanying drawing, Fig. 1 is a sectional view of the burner on line 1—1 of Fig. 5. Figs. 2, 3, 4 and 5 are detail views on a reduced scale. Fig. 2 is a plan view of a metallic holder for an asbestos wick. Fig. 3 is a bottom plan view of the spreader-cap. Fig. 4 is a side view of the wick holder and wick contained therein. Fig. 5 is a plan view of the liquid fuel burner.

Referring now to the drawing in which like characters indicate like parts, the invention includes a receptacle 6 having an annular chamber 7 or retort element open at its top, its inner wall 8 providing a flue 9, upon the top of said inner wall being removable seated a spreader-cap 10.

Numeral 11 indicates a collar which is disposed in the flue 9 and is connected with the bottom of the receptacle to provide a conduit 12, having a discharge pipe 13.

Numeral 14 indicates a supply pipe for the chamber 7, and in order that liquid fuel may be delivered uniformly to the upper part of the chamber I provide the annular, asbestos wick 15 supported upon the annular prop or distributing-ring 16. Asbestos is used for the wick since it will not become injured by action of heat, and is preferably secured between two annular, metallic walls *a* and *b* by means of suitable keepers *c*, parts *d* of the wick projecting somewhat above and below the ends of said walls; and the annular container 17 thus provided for the wick may be readily deposited in or removed from the chamber 7, the latter preferably having a greater area at its top than at the bottom. And when a sufficient quantity of liquid fuel enters the chamber 7 to cause it to become filled to the top of the head *e* of the ring 16, it will move upwardly by capillary attraction to the top of the wick in the recess *f* which is formed between the top of the wick and upper end of the chamber 7.

Numeral 18 indicates an annular flange which projects outwardly from the outer wall 19 of the chamber 7, said flange, as well as wall 19, having a sufficient thickness to permit heat to be communicated to and to be retained in the chamber 7 to advantage for facilitating the generation of gas, said chamber operating as a circular retort, during operation, for communicating an intense heat to its contents for this purpose.

Numerals 20 and 21 indicate annular depressions or grooves formed in the top of the flange 18, each having an upright wall *g*. The bottom of the cap 10 is provided with radially disposed wings 22 each having a part disposed in the flue and a part adapted to overhang the chamber 7, the thickness of each wing being gradually increased outwardly from the middle of the cap as best shown in Fig. 3; and the thickness of each wing is increased upwardly from its sharp, lower edge *h* to the body of the cap, each wing also having a terminal part *k* projecting beyond the periphery of the cap.

As described, constricted passageways *m* are formed between the body of the cap and the top of the wall 8, the edge of the cap 10 being disposed outwardly of said wall, and on account of the construction as de-

scribed all of the parts operate to great advantage for generating gas and permitting combustion effectively with a minimum of loss or waste of gas.

- 5 In operation, air will move outwardly from the constricted passageways *m* and will become mixed with the gases. However, in some instances the draft may be so strong that the gases or a certain proportion
 10 thereof might be lost, and therefore the inclined flange 18 and its depressions operate to advantage. The gases while moving outwardly will be deflected and broken up by the walls *g* as well as by the annular wall *n*
 15 of the recess *f*, said walls operating as detents or obstructions to said movements, and thereby combustion will be practically complete.

It will be noted that the flange 18 is inclined upwardly and outwardly from the wall 19 and therefore the outer depression 21 is disposed in a plane somewhat above the plane of the depression 20, so that these walls will partly obstruct the line of movement of the hydrocarbon mixture, this construction being obviously a feature of advantage.

Also it will be seen that the wall 8 for the chamber 7 has a lesser height than the flange 18, and therefore any overflow of liquid fuel from said chamber which might be occasioned by accident or otherwise will move downwardly along the inner side of the wall 8 into the conduit 12 and will be conducted
 30 from the burner by the pipe 13, as a safety measure.

The considerable degree of thickness of the wings at their ends provide a protected location or housing for the maintenance of pilot lights, and in operation, if the supply of liquid fuel to the chamber 7 is terminated by use of the valve 23 and when the generation of gas, on this account ceases, ignited gas will be retained at the ends of the wings for a considerable period of time thereafter, this obviously being a matter of convenience.

While I have shown a container 17 for asbestos and prefer its use, this container may be dispensed with, and in practice the asbestos may be placed to fill that part of the chamber 7 between the head *e* of the distributing ring and the recess *f*. Also while asbestos is preferred I may use other kinds of material as a filler. Also while I have shown four wings for the cap, this is not important and three or more wings may be used.

It will be noted that the upper walls of the air passageways between the wings 22 are of concave form, this feature being of advantage to permit the heated air in the flue and which occupies, comparatively, a large area, to move freely to the constricted passageways *m* while moving toward the generated gases.

While I have shown only two depressions 20 and 21 for the inclined flange 18, I do not wish to be limited to the exact number of depressions. Also I do not wish to be understood as limiting myself to the depressions 70 and their walls *g*; and the inclined flange may be provided with any kind of detent members tending to obstruct, or deflect or break up the outwardly moving gases to facilitate combustion and prevent waste of 75 gas.

It will be noted, as shown in Fig. 1 of the drawings, that the curvature of the concaved walls *w* of the spreader-cap extends outwardly of the inner wall 8 of the annular chamber 7, the degree of curvature of these walls being practically uniform to their terminals *t*, said terminals being disposed above the retort or chamber 7, the result in 80 operation being that air, while moving upwardly through the flue will be directed downwardly toward the top of the wick to cause a more thorough mixture of air with the generated gases, and thereby tending to cause a more complete combustion. 85

While I have shown a conduit 12 as an integral part of the receptacle I do not wish to limit myself in this respect, and it is obvious that operation would be the same if the conduit were attached to or carried by 90 the receptacle in such a manner that any overflow of liquid fuel moving downwardly in the flue would be received and conducted from the burner.

I claim as my invention:—

1. In a liquid fuel burner, an upright, annular chamber having its outer wall provided with an annular flange projecting outwardly from its upper end, a distributing ring in the chamber, an asbestos wick on said ring, a supply pipe communicating with the chamber, a spreader-cap on the inner wall of the chamber inwardly of the flange, said flange being provided at intervals radially thereof with a series of annular depressions, each outer depression being disposed in a plane above an inner depression. 105

2. In a liquid fuel burner, an upright, annular chamber open at its top and having its inner wall provided with a conduit, its outer wall being provided with an annular outwardly projecting flange disposed in a plane above the top of said inner wall, a dispensing-ring in the chamber, a wick in the chamber above said ring, a supply pipe for the chamber, a discharge pipe for the conduit, and a spreader-cap disposed inwardly of said flange on a wall of the chamber, said flange being provided with a series 110 of annular depressions disposed in spaced relation one of said depressions being disposed in a plane above another depression. 115

3. A liquid fuel burner comprising an upright, annular chamber having its outer wall provided with an annular flange projecting 120

outwardly from its upper end, a wick member having annular walls with an asbestos filler between said walls and disposed in said chamber, a supply pipe communicating with said chamber, a spreader cap on the inner wall of said chamber inwardly of said flange, said flange being provided at inter-

vals radially thereof with a series of annular depressions, one depression being disposed in a plane above another depression. 10

In testimony whereof, I have affixed my signature.

LEWIS A. COCKLIN.
